UNITED STATES PATENT OFFICE.

WILL R. JOHNS, OF ROCKFORD, ILLINOIS, ASSIGNOR TO THE EXCELSIOR AUTOMATIC KNITTING MACHINE COMPANY, OF NORRISTOWN, PENNSYLVANIA.

THREAD-FEEDING MECHANISM FOR KNITTING-MACHINES.

SPECIFICATION forming part of Letters Patent No. 600,788, dated March 15, 1898.

Application filed September 1, 1892. Serial No. 444,839. (No model.)

To all whom it may concern:

Be it known that I, WILL R. JOHNS, a citizen of the United States, residing at Rockford, in the county of Winnebago and State 5 of Illinois, have invented certain new and useful Improvements in Thread-Feeding Mechanism for Knitting-Machines, of which the following is a full, clear, and exact description, reference being had to the accompanying 10 drawings, forming a part of this specification.

This invention pertains to devices of novel construction for automatically combining with the usual or main thread of a knitting-machine, at predetermined intervals during 15 the process of knitting, an additional or supplemental thread, whereby certain portions of the fabric—as, for example, the heel, toe, or knee part of a stocking—may be thickened or reinforced to increase the durability 20 thereof.

The invention comprises means whereby the supplemental thread is led to and connected with the main thread; means whereby the supplemental thread is freed and permitted 25 to be carried to the needles by and with the main thread; means whereby said additional thread is severed at a prescribed period, and means whereby its free or leading end is retained in proper position for a 30 succeeding operation, all as will be hereinafter described in detail and be duly claimed.

In the annexed drawings, Figure 1 is a longitudinal vertical section of the invention as applied to a circular-knitting machine. Fig. 35 2 is a front elevation, the thread being in the grasp of the clamping device preparatory to the winding operation. Fig. 3 is a similar elevation, the thread being freed. Fig. 4 is a detail of a pattern mechanism for controlling 40 the operation of the yarn-guide devices. Fig. 5 is a separate view of the trip device for opening the clamp.

The numeral 1 represents the needle-support of the machine; 2, its needles; 3, the cam-carrier; 4, the knitting-cams therein, and 5 jacks operatively connecting the needles with the knitting-cams. The reciprocative action of the needles to effect the knitting of the web is the same as usual. So far 45 50 as the details of construction of the cams and their connection with the needles are con-

cerned these have no bearing upon the present invention. For illustration of these parts I have represented a portion of the machine set out in an application for Letters Patent 55 filed by me September 1, 1892, Serial No. 444,841.

Secured to the supporting-base 6 is a post or standard 7, the lower end of which is flanged to support the bobbins 8 and 9, and 60 the upper end of which is provided with an inwardly-extending arm 10. To this arm is connected the usual spring-actuated take-up lever 11, through the hooked forward portion of which the main knitting-thread 8^a extends 65 on its passage to the thread-carrier 12. On this arm is fixed an angular bracket-piece 13, the vertical member of which is provided on its forward face with a circular boss or projection 14, which is centrally perforated for 70 the passage of the main knitting-thread. This boss or projection is provided at a point above the central perforation with another perforation 15 for the passage of the supplemental or reinforcing thread 9^a hereinafter 75 described. Mounted on said boss or projection is a skeleton pinion 16, the teeth of which engage with those of a spur-wheel 17 on a suitably-disposed stud on the post 7, whereby when this wheel is rotated the pinion will be 80 operated. This pinion is equipped with a circular flange or ring 18, on the face of which is formed or secured a projection 19, forming an inwardly-curved hook or finger 20 with an outer radial offset or shoulder 21. The perforation 15 is in rear of the path traversed by the angle or corner of the hook and shoulder when the pinion is rotated. Pivoted on the face of the flange 18, in proximity to the hook 20, is a curved lever 22, the shorter arm 23 of 90 which projects into said angle and is normally pressed therein by a spring 24, which acts against the longer arm of the lever. Hence if the reinforcing-thread 9^a be drawn through the perforation 15 and the pinion be 95 rotated in the direction of the adjacent arrow, Fig. 2, the abutting faces of the lever-arm and hook will receive the thread and tightly clamp the same. If, then, the rotation of the pinion be continued, this end of 100 the thread will be twisted around the main thread as the latter is being fed to the needles.

This done, if the end be freed from the grasp of the arm and hook the supplemental thread will be carried to the machine by and with the main thread. It will be observed that 5 the drooping or "inward curving" of the hook, as I have termed it, and the outward curving of the coacting lever-arm form a flaring mouth to receive the supplemental thread. Although there is more than one way by which 10 the support for these thread-clamping devices may be operated and controlled, yet I prefer to use for this purpose a mechanism of the character illustrated in the drawings, the same comprising the aforescribed pinion 15 16 and spur-wheel 17, in conjunction with a small pinion 25, secured to the back of said spur-wheel concentrically therewith, and a vertically-reciprocating rack 26 in gear with the pinion, together with means for reciprocating said rack at predetermined intervals. It will be obvious that when the rack is reciprocated the coacting pinion and the spur-wheel will be rotated, which latter will thereupon by reason of the relative sizes of the 25 gears revolve the pinion 16 and its connections—to wit, the winder—very rapidly, thus effecting a close and tight winding or twisting of the supplemental thread upon the main thread.

30 The rack is formed or supported upon a vertical rod 27, which is connected with a suitably-disposed horizontal lever 28, to which movement is imparted at certain stages by means of tappets 29 on the face of a pattern-wheel 30. The latter is moved step by step by means of any suitable mechanism; but as such mechanism forms no part of the present invention no detailed description thereof is deemed necessary in this connection. A pattern-wheel 35 40 of this description, however, and operating devices therefor are set forth in detail in my other application above mentioned. Briefly described, the pattern-wheel is provided with peripheral ratchet-teeth with which coact 45 pawls *a* on a pivoted arm *b*, which is periodically operated by appropriate mechanism. The positions of the tappets upon the wheel 30 will of course determine the time when the supplemental thread is thrown into and out 50 of action. This thread, however, will most frequently be used during the formation of the heel-pouch of socks and stockings, the thread being thrown in at the commencement of the knitting of the pouch and being checked 55 or thrown out at the completion thereof.

Pivoted to a post 31, rising from the arm 10 adjacent to the pinion 16, is a trip device 32, comprising the depending arm 33, the finger 34, projecting over and above the flange of 60 the pinion, and a lip 35, projecting outwardly therefrom into the vertical path of the rack, whereby the latter in its upward stroke may be caused to strike the lip 35 and thus raise the same and depress the finger 34. The 65 function of the depending arm is a counterpoise to maintain the finger normally raised. Of course a spring could be very readily sub-

stituted for this arm. It will be observed that the shape of the spring-actuated arm of the thread-clamping lever 22 is such that normally—that is, when the supplemental thread is caught thereby—the edge of the arm extends beyond the periphery of the flange 18. Hence when the finger 34 is depressed, as above described, it will bear upon this projecting edge as the pinion turns and thus depress said arm to free the thread therefrom, as above mentioned. In the upward movement of the rack, the supplemental thread being in the grasp of the lever 22, the pinion 80 is rotated in the direction of the arrow, Fig. 2, thereby twisting or winding said thread upon the lower or main thread, as previously stated. The top of the rack-bar as it continues its upward movement will impinge 85 against the opposed lip of the trip device and effect the freeing of the supplemental thread to the end that it may be carried to the needle by and with the main thread. As a means whereby this supplemental thread may 90 be severed when its service has been performed I affix to the arm 10, immediately in front of the lever 22, a suitable knife or cutter 35^a, which in this instance comprises an angular piece the upper edge of the vertical 95 member whereof extends to or slightly above the horizontal diameter of the pinion, said edge being slightly inclined downwardly on one side of the center and being beveled to a sharp cutting edge, as indicated at 37. When 100 the rack is depressed, the pinion is rotated in a reverse direction to its former movement, the lever thereon when the finger is raised by the removal of the pressure of the rack-bar thus returning automatically to its normal 105 biting position against the corner of the hook. When the rack is again partially raised, the supplemental thread is grasped by the lever and hook, and as the pinion is rotated the thread is drawn down upon the sharp edge 110 of the cutter, thereby severing the thread. This done, the parts remain quiescent in readiness for a repetition of the above-described operation at a predetermined period. I would add that when the rack is raised in 115 the first place to effect the twisting of the thread, as above mentioned, such thread is not severed, because its end does not extend over the edge of the knife or cutter.

In certain claims hereinafter there is recited 120 as an element "means to hold the thread end previous to winding," which expression, it may be remarked, is designed to include not only thread-holding means secured to or forming a part of the winder, but also means separate from and independent of the winder.

I claim—

1. In a knitting-machine, the combination with a source of plural thread-supply, of a rotary winder for carrying the free end of one 130 thread one or more times about another.
2. In a knitting-machine, the combination with a source of plural thread-supply, of a rotary winder for carrying the free end of one

thread one or more times about another, and means for severing said thread.

3. In a knitting-machine, the combination with a guide device for a plurality of threads, 5 of a rotary winder for carrying the free extremity of one thread one or more times about another.

4. In a knitting-machine, the combination with a guide device for a plurality of threads, 10 of a rotary winder for carrying the free end of one thread one or more times about another, and means for holding said thread end previous to winding.

5. In a knitting-machine, the combination 15 with a guide device for a plurality of threads, of a rotary winder for carrying the free extremity of one thread one or more times about another, means for holding said thread end previous to winding, and means for severing 20 one end of said thread.

6. The combination of a guide device for the main and supplemental threads, a clamping device adapted to grasp the end of the supplemental thread, and means for rotating 25 said clamping device so as to twist or wind the supplemental thread upon the main thread, substantially as described.

7. The combination of the guide device for the main and supplemental threads, a clamping 30 device adapted to grasp the end of the supplemental thread, means for rotating said clamping device so as to wind or twist the supplemental thread upon the main thread, and means for severing the supplemental 35 thread, substantially as described.

8. The combination of a guide device for the main and supplemental threads, a clamping device adapted to grasp the end of the supplemental thread, means for rotating said 40 clamping device so as to twist or wind the supplemental thread upon the main thread, and means for opening said clamping device to free the end of the supplemental thread, substantially as described.

45 9. The combination of a guide device for the main and supplemental threads, a clamping device adapted to grasp the end of the supplemental thread, means for rotating said clamping device so as to twist or wind the 50 supplemental thread upon the main thread, means for opening said clamping device to free the end of the supplemental thread, and means for severing the supplemental thread, substantially as described.

55 10. The combination of a device provided with two thread-guides, a rotatable member

adapted to revolve around said guides, means for rotating said member, a clamping device mounted on said rotatable member in the path of one of said guides, and adapted to hold the 60 end of that thread which passes through said latter guide, and means for opening said clamping device to release the thread therefrom, substantially as described.

11. The combination of a device provided 65 with two thread-guides, a rotatable member adapted to revolve around said guides, means for rotating said member, a clamping device mounted on said rotatable member in the path of one of said guides, and adapted to hold the 70 end of that thread which passes through said latter guide, means for opening said clamping device to release the thread therefrom, and means for severing said thread, substantially 75 as described.

12. The combination of the guide device, the pinion, the spring-actuated clamping-lever and the opposed hook or finger on said pinion, means for rotating said pinion, and means for actuating the clamping-lever at 80 predetermined intervals, substantially as described.

13. The combination of the guide device, the pinion, the spring-actuated clamping-lever and the opposed hook or finger on said 85 pinion, a normally inactive trip device for opening said lever, and means for operating said trip device and pinion at predetermined intervals, substantially as described.

14. The combination of the guide device, 90 the pinion, the spring-actuated clamping-lever and the opposed hook or finger on said pinion, a normally inactive trip device for opening said lever, and means for operating said trip device and pinion at predetermined 95 intervals, together with a thread-severing device, substantially as described.

15. The combination of the guide device, the pinion, the spring-actuated clamp and the opposed hook or finger on said pinion, a 100 normally inactive trip device for opening said clamp, the spur-wheel for operating said pinion, the pinion connected with said spur-wheel, and the rack engaging said latter pinion, substantially as described. 105

In testimony whereof I have hereunto affixed my signature in the presence of two subscribing witnesses.

WILL R. JOHNS.
